UNITED STATES PATENT OFFICE.

AUSTIN McINNIS, OF NORTHAM, CANADA.

TOBACCO-CUTTER AND PIPE-FILLER.

SPECIFICATION forming part of Letters Patent No. 779,095, dated January 3, 1905.

Application filed April 21, 1904. Serial No. 204,234.

To all whom it may concern:

Be it known that I, AUSTIN McINNIS, a subject of the King of Great Britain, residing in District 13, Northam, in the Province of Prince Edward Island, in the Dominion of Canada, have invented a new and useful Improvement in Tobacco-Cutters and Pipe-Fillers, of which the following is a specification.

The object of this invention is a mechanical pipe-filler adapted to hold smoking-tobacco in the form of plugs and to automatically cut the tobacco as the pipe is filled.

A further object of the invention is to provide a convenient device which will not only cut the tobacco and fill the pipe-bowl, but which will also serve as a storage-receptacle for the uncut tobacco and also for matches and which will be of a convenient size to carry in the pocket.

My invention consists of the novel features of construction hereinafter described, particularly pointed out in the claims, and shown in the accompanying drawings, in which—

Figure 1 is a perspective view of my device, 25 a pipe being shown in position to have the bowl filled. Fig. 2 is a longitudinal section drawn on the line 2 2 of Fig. 5, the mechanism being shown in elevation and the lower portion of one of the inner walls being broken 30 away. Fig. 3 is a vertical transverse section on the line 3 3 of Fig. 2, the elastic band being omitted. Fig. 4 is a longitudinal sectional view on the line 4 4 of Fig. 3, the cutter being shown in vertical elevation. Fig. 5 is a 35 horizontal section on the line 5 5 of Fig. 4, portions of the actuating-levers being broken away. Fig. 6 is a detail perspective view of one of the plungers. Fig. 7 is a detail view of a portion of the T-shaped feed-lever.

In the drawings, A represents an oblong metal casing rounded at the forward end and closed at the rear end by a hinged door A', fastened by any suitable latch or spring-catch. The casing has a non-perforate top; but the 45 bottom of the casing has adjacent the forward end of the casing A an opening A², having a diameter approximately that of the ordinary pipe-bowl. An elastic band B has its ends secured to the sides of the casing adjacent the 50 opening A², the central portion of the band B

depending in a loop below and transverse to the opening A².

Arranged within the casing A is an inner casing C, and this inner casing is formed with a double wall, the additional wall C' extending from the rear end of the casing A to a line adjacent the forward end. This additional inner wall C' is duplicated upon opposite sides of the casing C and is spaced from the said casing, and at the forward end of each inner wall C' the wall is bent outwardly, terminating against the inner face of the wall of the casing C. This space between the two inner walls C' forms a chamber D, open at both ends and having a width equal to the average width 65 of plugs of smoking-tobacco. The rear end of this chamber D is closed by the door A'. The front wall of the casing C is curved to conform to the curvature of the front wall of the outer casing A, and the bottom C² of the 70 casing C is some distance above the bottom of the casing A. This construction forms a chamber E, also closed at the rear by the door A', in which matches may be carried. The top wall of the casing C is also spaced from the 75 top of the casing A, and the forward end of the chamber E is closed by the vertical wall E'.

Arranged in the forward end portion of the casing C and in advance of the inner walls C' is an auger-shaped vertically-arranged spiral 80 cutter F, the lower edges of the convolutions of the spiral forming a continuous rotatable cutting-blade. The upper stub end of this spiral cutter F extends through the top wall of the casing C and is journaled in the inner 85 face of the top of the casing A, and between the two casings there is rigidly mounted upon this stub portion a beveled gear-wheel F'.

On each side of the casing C and within the casing A are journaled beveled gear-wheels F², 90 each intermeshing with the gear-wheel F'. To the projecting stub-shaft of one of the beveled gear-wheels F² is hinged a crank and handle F³, by which the gear-train above described may be actuated. A recess G is formed in the 95 forward portion of the casing A, and the crank-handle F³ being hinged the handle portion will rest in said recess when not in use. The inner faces of the beveled gear-wheels F² are spaced apart from the sides of the casing 100

C and carry pins F⁴, the pins being arranged diametrically opposite each other, so that when the pin F⁴, carried by one of the gear-wheels F², reaches the highest point in its revolution the similar pin carried by the other gear-wheel F² will be at the lowest point of its revolution.

The mechanism arranged between the sides of the casings A and C are similar, and a description of the levers and spring on one side will suffice for the mechanism on the opposite side, it being remembered that the opposite arrangement of the pins F⁴ will result in simultaneous movements in opposite directions of the mechanism actuated by the pins and on opposite sides of the casings C.

To the side of the casing C is pivoted the lever H, the free end of the lever extending between the bevel gear-wheel F² and the side of the casing C and resting loosely on the pin F⁴. Below the lever H is pivoted a lever J, the free end portion being offset and spaced from the wall of the casing C, and adjacent its free end this lever J is slotted, as at J'. Working vertically in the forward end of the casing C and arranged on opposite sides of the spiral cutter F are plunger-bars J², carrying at their lower ends plungers J³, having the form of a transversely-split metal band. The lever J above mentioned engages a pin J⁴, the inner end of the pin fitting rotatably in a socket formed in the upper end of the plunger-bar J² and the outer end of the pin resting in the slot J'. It will be understood that the remaining plunger-bar J² is similarly connected to a similar lever upon the opposite side of the casing C. The levers H and J are connected by a lever K, pivoted at its upper end to the lever H and at its lower end to the lever J. The side of the casing C is cut out, whereby the openings L are formed in vertical alinement. A feed-lever M, having a T-head M' at its forward end, is pivoted at its rear end to the lever or link K, the pivotal point being adjacent the end of the lever or link K, pivoted to the lever H, and the head M' works on a pivot-pin M², carried by the side of the casing C. The ends of the T-head M' carry inwardly and forwardly extending prongs M³, which work through the openings L.

The manner of using and operating my device is as follows: The tobacco is placed in the chamber D and is engaged on each side by the prongs M³ of the T-heads M', which tend to prevent rearward movement of the tobacco. When the pipe-bowl is to be filled, it is placed within the elastic band B, as shown in full lines in Fig. 1 and in dotted lines in Figs. 2 and 3. By rotating the handle F³ the bevel-gears F² and F' will be rotated and a rotatory movement will be given to the cutter F. The levers H will be rocked by the pins F⁴, and as the pins F⁴ approach and reach the high point 65 in their revolution the free ends of the levers

H, there being one on each side of the casing, will be raised and through the medium of the connecting-links K the levers J will receive vertical movement and the plunger-bars J² will be raised. As a pin F⁴ passes the highest point in its revolution it slips from under the free end of the lever H, with which it has been in engagement, and a spring N, connected to the lever J, forcibly draws downward the said lever, resulting in downward movement of the plunger-bar J² in engagement with the slot J' of the said lever J, this movement being permitted by a vertical slot L', formed in the side of the casing. The movement of the pivoted link K as the lever H rises and falls will impart a rocking movement to the T-head M' about its pivotal point M², and the prongs M³ will be alternately advanced and retracted, and as these prongs slant in a forward direction the tobacco will be pressed forward against the cutter and as it is cut it will be fed and properly packed in the pipe-bowl by the plunger-heads J³. It will be further noted that as a prong M³ is moving in a forward direction on one side of the casing C the corresponding prong upon the opposite side is moving rearwardly.

Having thus fully described my invention, what I claim as new, and desire to secure by Letters Patent, is—

1. A device of the kind described comprising a cutter, plungers adapted to work adjacent and below the cutter, means for operating the cutter and plungers and means for feeding tobacco to the said cutter.

2. A device of the kind described comprising a casing adapted to contain tobacco, a spiral cutter, plungers working below the said cutter, means for rotating the cutter and reciprocating the plungers and means carried by the casing for automatically feeding the tobacco to the cutter.

3. A device of the kind described comprising a casing adapted to contain tobacco said casing having an opening in the bottom, means for holding a pipe-bowl below said opening, a spiral cutter arranged within the casing above the opening, plungers adapted to work through the opening and project into the pipe-bowl when the cutter is rotated, means for actuating the plungers, means for automatically feeding tobacco to the cutter, and means for rotating the cutter.

4. A device of the kind described comprising a spiral cutter, means for holding a pipe-bowl below the said cutter, a receptacle adapted to contain tobacco, means for rotating the cutter, a pronged, T-head lever carried by the receptacle and adapted to feed the tobacco to the cutter and means for actuating the lever.

5. A device of the kind described comprising a casing adapted to contain tobacco, said casing having an opening in the bottom adjacent its forward end, a spiral cutter vertically

arranged in the forward end of the casing above the said opening, the cutter terminating at its upper end in a shaft, a bevel gear-wheel on the said shaft, intermeshing beveled gears, pins carried by said gears, levers pivoted to the casing at one end and having their free ends adapted to be engaged by the said pins, plunger-bars adapted to work through the opening in the bottom of the casing, levers pivoted to the casing below the first-mentioned

levers and connected at their free ends to the plunger-bars, links pivotally connecting the upper and lower levers, a T-headed feed-lever pivoted to the link adjacent the upper lever on each side of the casing, and means for rotating the gears. 15
